UNITED STATES PATENT OFFICE.

JOEL EWING WILLIAMSON, OF EVANSVILLE, INDIANA.

TELEPHONE ATTACHMENT.

1,274,128.

Specification of Letters Patent. Patented July 30, 1918.

Application filed October 8, 1917. Serial No. 195,375.

To all whom it may concern:

Be it known that I, JOEL EWING WILLIAMSON, a citizen of the United States, residing at Evansville, county of Vanderburg, and 5 State of Indiana, have invented certain new and useful Improvements in Telephone Attachments, of which the following is a specification.

This invention relates to telephone attachments.

My object is to provide an attachment for a subscriber's telephone desk set which will prevent the telephone cord from wrapping around the instrument or becoming tangled.

15 The invention contemplates the provision of an improved joint or turn-table between the base and the standard of the instrument, one embodiment of which is set forth hereinafter and shown in the accompanying 20 drawings, in which—

Figure 1 is a side elevation of a subscribers' telephone to which the invention has been applied, certain parts being broken away and others in section; and

25 Fig. 2 is a detail view of the attachment.

The base of a subscriber's telephone appears at 1, the standard at 2, and the cord at 3.

30 In the ordinary subscriber's instrument the standard and base are rigidly connected together; consequently the cord 3 becomes tangled and is frequently involuntarily wrapped around the standard by the user.

To prevent the tangling and twisting of 35 the cord 3, I mount the standard 2 in a rotatable manner on the base 1. An attachment which may be employed for the foregoing purpose is shown in Fig. 2, comprising a collar 4, flange 5, hub 6, and shank 7.

40 The collar receives the lower end of the standard 2 and is secured thereto by screws 8. The base 1 has an opening 9 slightly larger than the hub 6 in which the said hub is rotatably received. The flange 5 rests

upon the base 1 and supports the standard 2. 45 A ball cage or race 10 fits around the hub 6 and also around shank 7; balls 11 are contained within the cage or race and bear on the lower face of the hub 6. The upper end of the cage 10 engages the base 1. A spring 50 12 surrounds the shank 7 and is held against the bottom of cage 10 by a cotter 13.

The foregoing attachment mounts the standard 2 so that it will revolve on the balls 11; consequently it turns in relation to the 55 base at the slightest touch and prevents tangling, twisting or wrapping of the cord 3.

Having thus described my invention, what I claim as new and desire to secure by Letters Patent, is:—

1. A subscriber's telephone comprising a 60 base and standard which are relatively rotatable, and a cord wholly carried by the standard and entering the side thereof.

2. A subscriber's telephone comprising a 65 base and standard which is rotatable in relation to the base, and a cord for the instrument which enters, and is carried solely by, the standard.

3. A subscriber's telephone comprising a 70 base, a standard, an anti-friction joint between the two, whereby they are relatively rotatable, and a cord wholly carried by the standard.

4. A subscriber's telephone comprising a 75 base, a standard, and a standard-supporting coupling between the two which is secured to the standard and is rotatable in relation to the base.

5. A subscriber's telephone comprising a 80 base, a standard, and a coupling between the two which has a flange resting on the base, a hub rotatable in the base, a shank, a ball cage or race, balls in said cage, and a spring interposed between the cage and shank. 85

In testimony whereof I hereunto affix my signature.

JOEL EWING WILLIAMSON.
